UNITED STATES PATENT OFFICE.

CHARLES A. LINDSTRÖM, OF PITTSBURGH, PENNSYLVANIA, ASSIGNEE TO PRESSED STEEL CAR COMPANY, OF PITTSBURGH, PENNSYLVANIA, A CORPORATION OF NEW JERSEY.

CAR END CONSTRUCTION.

1,119,845.

Specification of Letters Patent.

Patented Dec. 8, 1914.

Application filed March 11, 1911. Serial No. 613,710.

To all whom it may concern:

Be it known that I, CHARLES A. LINDSTRÖM, a citizen of the United States, residing at No. 138 Stratford avenue, Pittsburgh, 5 E. E., in the county of Allegheny and State of Pennsylvania, have invented certain new and useful Improvements in Car End Construction, of which the following is a specification.

10 This invention relates to metallic railway cars, more especially to the end construction thereof, and particularly to the end stakes and method of fastening them to coöperating parts. Owing to the outward pressure 15 of the lading within the car body and its tendency to bow or bulge out the end of the car body when the train is suddenly started or stopped, it becomes desirable to provide some especially strong and firm means to 20 maintain the end wall in normal position. Since the outward strain on the end stakes is least at their tops, and gradually increases toward their lower ends, it is evident that to economize metal the stakes should be 25 tapered, being deepest or thickest at their lower ends. As a flange along the inner edge of the stake affords a convenient means for attachment to the end wall of the car, and a flange along the outer edge affords a 30 similar means for attachment at its lower end to the end sill, I use stakes of channel section, varying in depth throughout their length. The anchorage of the root or lower end of these stakes is an important feature, 35 and to secure an especially rigid and strong connection, I extend the longitudinal sills of the car beyond the vertical plane of the end wall of the car. To the outer ends of these longitudinal sills are secured the end sills 40 which may be of channel or other suitable form. The lower ends of the end stakes pass downwardly between the vertical planes of the outer surface of the end wall, and the inner surface of the end sill, and 45 are secured through the medium of their flanges and by rivets or other suitable means to both the end wall and end sill. I am aware that it is old in the art, to extend the lower ends of end stakes downwardly in this 50 manner, and to secure them to the draft sills or center sills of the car, but in the construction referred to the support afforded to the end wall of the car by the end stakes is not distributed to the best advantage, being 55 too near the center of the end of the car;

whereas, my invention provides for the location of two or more stakes located in positions best adapted to give the necessary amount and distribution of support to the end wall of the car.

In the accompanying drawings, which form a part of this specification, and in which like reference characters refer to the same parts throughout, I have illustrated the preferred embodiment of my invention.

Figure 1 is an end view of one end of a railway car built in accordance with my invention; Fig. 2 is a vertical longitudinal section of a portion of one end of the car, and Fig. 3 is a plan view thereof, partly in section.

The body of the car may be constructed in various ways, that shown in the drawings being wholly metallic; but it will be understood that the invention is equally as well 75 adapted to a car having a wooden body. The car body shown has side plates 1, floor plates 2, and end plates 3, all of these parts being secured together in the usual or any preferred manner. The car shown is provided with an underframe having the usual center sills 4, end sill 5 and end sill cover plates 6.

The end stakes 7 are preferably tapered toward their tops as shown, and are also 85 preferably of general channel shape as shown, with web portion 8, extending at right angles to the end wall and having the inner flange 9 suitably secured to the end wall. These stakes extend downwardly sufficiently far to permit the lower ends of their outer flanges 12, to be secured to the inner side 10 of the end sill 5; the ends of the inner flanges 9, as also a portion of the web 8, being cut off at an angle as shown by 95 line 11, Fig. 2. As a result of this connection, the end stakes are very rigidly secured in place, so that the upper ends thereof cannot be pushed outwardly by pressure of the lading against the end wall, and such connection will enable these stakes to withstand any load or stress insufficient to bend the stakes themselves. The downward extension of these stakes results in another advantage, inasmuch as they constitute very 105 efficient braces for the end sills, resisting deformation of the end sill in the event of accidental blows resulting from rough usage, collision or other accident.

Although I have illustrated and described 110

my invention as embodied in a gondola car, it will be readily understood that it is not limited to such use, and that various mechanical changes may be made in the structure without departing from the principle or substance of my invention or the sacrifice of any of its benefits.

Having thus described my invention, what I claim and desire to secure by Letters Patent is:—

1. In a car, the combination with the center sill, end wall and end sill, of a stake of channel section of variable depth, having flanges of unequal length on the opposite edges of its web, one of said flanges being secured to the outer side of the end wall and the other flange being secured to the inner side of the end sill.

2. In a car, the combination with the center sill, end wall and end sill, of a stake of channel section of variable depth, having flanges of unequal length on the opposite edges of its web, one of said flanges being secured to the outer side of the end wall and the other flange being secured to the inner side of the end sill, said stake being out of contact with the center sill.

3. In a car, the combination with the center sill, end wall and end sill, of a stake of channel section of variable depth, having flanges of unequal length on the opposite edges of its web, one of said flanges being secured to the end wall and the other flange being secured to the inner side of the end sill, the flange secured to the end sill being of greater length than the flange secured to the end wall.

4. In a car, the combination with the center sill, end wall and end sill, of a stake of channel section of variable depth, having flanges of unequal length on the opposite edges of its web, one of said flanges being secured to the end wall and the other flange being secured to the inner side of the end sill, the flange secured to the end sill being of greater length than the flange secured to the end wall, said stake being out of contact with the center sill.

5. In a car, the combination with the center sill, end wall and end sill, of a stake of channel section, of greater depth at one end of its channel portion than at its other end, having flanges of unequal length on the opposite edges of its web, one of said flanges being secured to the outer side of the end wall and the other flange being secured to the inner side of the end sill.

6. In a car, the combination with the center sill, end wall and end sill, of a stake

of channel section of greater depth at one end of its channel portion than at its other end, having flanges of unequal length on the opposite edges of its web, one of said flanges being secured to the end wall and the other flange being secured to the inner side of the end sill, the flange secured to the end sill being of greater length than the flange secured to the end wall.

7. In a car, the combination with the center sill, end wall and end sill, of a stake of channel section of greater depth at one end of its channel portion than at its other end, having flanges of unequal length on the opposite edges of its web, one of said flanges being secured to the end wall and the other flange being secured to the inner side of the end sill, the flange secured to the end sill being of greater length than the flange secured to the end wall, said stake being out of contact with the center sill.

8. In a car, the combination with the center sill, end wall and end sill, of a stake of channel section, reduced in depth at one of its ends, having flanges of unequal length on the opposite edges of its web, one of said flanges being secured to the outer side of the end wall and the other flange being secured to the inside of the end sill.

9. In a car, the combination with the center sill, end wall and end sill, of a stake of channel section reduced in depth at one of its ends, having flanges of unequal length on the opposite edges of its web, one of said flanges being secured to the end wall and the other flange being secured to the inside of the end sill, the flange secured to the end sill being of greater length than the flange secured to the end wall.

10. In a car, the combination with the center sill, end wall and end sill, of a stake of channel section reduced in depth at one of its ends, having flanges of unequal length on the opposite edges of its web, one of said flanges being secured to the end wall and the other flange being secured to the inside of the end sill, the flange secured to the end sill being of greater length than the flange secured to the end wall, said stake being out of contact with the center sill.

11. A car stake of channel section being tapered at one side toward its top and tapered at the other side toward its bottom.

In testimony whereof I affix my signature in presence of two witnesses.

CHARLES A. LINDSTRÖM.
